[57] CLAIM

The ornamental design for a coffee bean confection, as
shown and described.

DESCRIPTION

FIG. 1 is a perspective view of a coffee bean confection
showing the design;

FIG. 2 is a right side elevational view thereof;

FIG. 3 is a left side elevational view thereof;

FIG. 4 is a front elevational view thereof;

FIG. 5 is a top plan view thereof, the bottom plan view being
identical; and,

FIG. 6 is a rear elevational view thereof.

The broken line showing on FIGS. 1 and 2 is for illustrative
purposes only and forms no part of the claimed design.
